UNITED STATES PATENT OFFICE.

JAMES A. CAMERON, OF BROOKLYN, NEW YORK.

MACHINE FOR SLITTING FABRICS.

No. 904,247.

Specification of Letters Patent.

Patented Nov. 17, 1908.

Application filed January 13, 1908. Serial No. 410,533.

To all whom it may concern:

Be it known that I, JAMES A. CAMERON, a citizen of the United States, and a resident of Brooklyn, in the county of Kings and State of New York, have invented certain new and useful Improvements in Machines for Slitting Fabrics, of which the following is a specification.

The invention relates to improvements in machines for slitting a traveling fabric into any required number of strips, and it consists in the novel features and combinations of parts hereinafter described and particularly pointed out in the claims.

15 The object of the invention is to provide a comparatively inexpensive highly efficient machine capable of uniformly dividing a width of fabric caused to travel through it into a number of strips for use in the various arts requiring them.

20 The machine comprises any suitable means for drawing a fabric from a roll or bolt through the machine, a tension device through which the fabric passes and which 25 in effect irons it out, a series of cutting disks mounted on a rotary shaft, a series of pressure or bed-disks against which said cutting disks slit the traveling fabric, and novel mechanism connected with and utilized for 30 positioning said pressure or bed-disks.

The invention will be fully understood from the detailed description hereinafter presented, reference being had to the accompanying drawings, in which:

35 Figure 1 is a front elevation, partly broken away, of a machine constructed in accordance with and embodying the invention; Fig. 2 is a side elevation, partly broken away, of the same; Fig. 3 is a central vertical longitudinal section, partly broken away, of the same; Figs. 4 and 5 are detail longitudinal sectional views of a portion of the machine and are presented to illustrate two 40 positions of the mechanism connected with 45 and provided for positioning the pressure disks which afford a bed against which cutters may act when the parts are in the position represented in Fig. 3; Fig. 6 is an enlarged detached perspective view of one 50 of the bars for carrying at their inner ends the pressure or bed-disks; Fig. 7 represents in detail the spring and its parts for connection with the outer end of the bar shown in Fig. 6; Fig. 8 is a detached perspective 55 view of one of the short axles applied to the

inner ends of the bars one of which is shown in Fig. 6 and upon which axles the pressure or bed-disks are rotatively mounted within the forked inner ends of said bars; Fig. 9 is a detached top view illustrating a portion 60 of a slitted fabric with a portion of the cutters thereon; Fig. 10 is a detached top view illustrating a portion of a fabric having the slits cut on the bias of the same, and Fig. 11 is a detached perspective view, 65 partly broken away, of a bifurcated shoe for holding the bar shown in Fig. 6 in position on the rod or shaft supporting it.

In the drawings 15 designates a suitable supporting fabric for the operative parts of 70 the machine, 16 a length of fabric passing through the machine to be reduced to strips thereby, 17 a shaft carrying a series of cutting disks 18 to act upon the traveling fabric, 19 a series of pressure or bed-disks between 75 which and the cutters 18 the traveling fabric passes, 20 a winding drum or reel for winding upon itself the slitted fabric leaving the cutters, and 21 a tension device through which the fabric passes from any suitable 80 source on its way to the cutters 18 and pressure disks 19.

The shaft 17 has mounted upon it the cutting disks 18 which are suitably spaced by collars 22, and said shaft receives its rotary 85 motion from a driving or power wheel 23 through a pinion wheel 24 on the stud 25 and an intermeshing gear wheel 26 on one end of said shaft. On the other end of the shaft 17 are provided a hand operating- 90 wheel 27 and a belt-wheel 28, the latter of which is utilized in connection with a belt or cord 29 and belt-wheel 30 for imparting motion to the reel 20, which may be of any usual or suitable character. 95

Extending between the sides of the machine in advance of the lower edges of the cutters 18 is a bed-plate 31 (Fig. 3) over which the fabric 16 passes and which supports and directs it to the cutters, and at the front of said plate 31 is provided the tension device 21 which comprises, in the present instance, rods 32, 33 and end-plates 34, said rods 32 being extended between the side frames of the machine and secured thereto, 100 and said rods 33 being secured to and carried by the plates 34, which are pivotally mounted at their inner ends on the ends of the inner rod 32 so that they may have a hinged movement thereon, as denoted by 110

dotted lines in Fig. 3. The rods 32, 33 are normally in horizontal alignment and alternate with one another, the rods 33 being at opposite sides of the front rod 32. The fabric 16 passes above the rods 32 and below the rods 33, whereby said fabric is compelled to travel an irregular course under the pressure exerted by the rods 33. The plates 34 are recessed, as at 35, to pass upon the ends 10 of the front rod 32, which is adapted thereby to support said plates when they are in their lower position, as shown by solid lines in Fig. 3. The plates 34 and rods 33 may be readily elevated or turned upwardly, as denoted by dotted lines, when it is desired to introduce the end of the fabric through the machine, and thereafter lowered upon the fabric to, in connection with the rods 32, create the proper tension on the latter and 20 remove or iron out any irregularities in the same, this tension device also assuring the proper feed of the fabric to the cutters and the uniform slitting of the same. The tension device 21 is simple in construction and 25 easily handled and also highly efficient in use.

The pressure-disks 19 are preferably of metal and there is one of these disks directly below each cutter 18. The disks 19 are each 30 rotatively mounted on a short spindle or shaft 36 (Fig. 8) having flat-sided ends set within vertical recesses 37 (Fig. 6) formed in the sides of the rear forked end of a longitudinal bar 38, the disk 19 being between the 35 sides of the fork. There are as many bars 38 as there are disks 19 and cutters 18, so that each bar may independently carry a disk 19 for a cutter, and each bar 38 is recessed to set and rock upon the transverse shaft 41 40 upon which all the bars 38 are mounted. The bars 38 are held in position by bifurcated shoes 39 secured on the shaft 41 by screws 57. The front ends of the bars 38 45 have flexed against them the leaf springs 42, whose rear ends are provided with shoes 43 (Fig. 7) to receive them and pass into inclined recesses 44 in the front ends of the bars 38, said shoes being recessed on their upper and lower sides, as at 45, to engage the 50 walls and edges of said recesses and thereby become secure against edgewise movement in their position therein. A screw 46 is also provided for fastening each shoe 43 in its recess 44. The front ends of the springs 42 55 carry adjusting screws 47 whose ends engage the lower surface of a transverse bar 48 constituting a portion of the frame of the machine. The springs 42 press upwardly against the bar 48 and downwardly against 60 the bars 38, and when the parts are in the position shown in Fig. 3, said springs exert their force to yieldingly press the disks 19 upwardly against the cutters 18. The tension of the leaf springs 42 may be adjusted 65 by the screws 47.

The ends of the shaft 41 have flat sides to guide vertically in the slotted sides of the machine frame (Fig. 2), and below said ends and supporting the shaft 41 are cams 49 secured on a transverse shaft 50, which may have an oscillatory or rotary motion imparted to it, for actuating said cams 49, by means of a handle 51 applied on the end of the same. I may apply as many cams 49 on the shaft 50 as may be required by the size 70 of the machine and the work it is to perform and in the drawings I show four cams on said shaft. The shaft 50 has bearings in the sides of the machine and is also supported from a transverse bar 52 (Figs. 1 and 3) by 80 standards 53 whose upper ends afford bearings for said shaft. The cams 49 have an eccentric surface 54, a depressed surface 55 and a more greatly depressed or flat surface 56, and each of these surfaces is made use of. 85 When the eccentric surfaces 54 of the cams 49 are turned upwardly against the shaft 41 they will elevate said shaft and bars 38 supported thereon to their upper position, shown in Fig. 3, and thereby move the pressure 90 disks 19 into operative relation to the cutters 18, the springs 42 being then flexed to their maximum extent and by pressing downwardly on the front ends of the bars 38 yieldingly forcing said disks against said 95 cutters. The bars 38 have a limited pivotal movement on the shaft 41, and lateral movement of said bars 38 is prevented by the shoes 39 fitting, at their recesses 40, said shaft 41. When the surfaces 54 of the cams 100 49 are turned from under the shaft 41 and the depressed surfaces 55 of said cams moved under said shaft, the latter may lower, as shown in Fig. 4, and thereby relieve the pressure disks 19 from the cutters 18, under 105 which condition the work may be adjusted or inserted below the cutters or otherwise manipulated. When the flat surfaces 56 of the cams 49 are turned below the shaft 41 the latter may lower to its maximum extent 110 or at rest position, as shown in Fig. 5, and under such condition the springs 42 will press the front ends of the bars 38 against a supporting rod 58 provided therefor.

I regard the means hereinbefore described 115 for mounting and manipulating the pressure disks 19 as of special value and importance in a machine for slitting fabrics. In the construction described I obtain a very firm and uniform though yielding pressure of the 120 disks 19 against the fabric traveling below the cutters, each disk 19 being independent of the others and adapted to meet such conditions as may arise with respect to that portion of the fabric over it. The series of 125 disks 19 form a cutting bed of independent rotary yielding sections and they are highly efficient in use.

In the employment of the machine, the pressure disks 19 being in their initial lower 130

position, the end of the fabric 16 will be carried over the front corner of the machine frame, thence through the tension device and over the bed 31 and thence between the cutters 18 and pressure disks 19 and to the reel 20, to which it will be connected. The pressure disks 19 will then be elevated to their operative position shown in Fig. 3 and the machine set in motion, with the result that 5 the traveling fabric will be drawn through the machine and slit by the cutters 18, and that the several severed strips will be wound upon the reel 20. When first introducing the fabric to the machine, the plates 34 carrying the tension rods 33 will be turned upwardly to the position shown by dotted lines 10 in Fig. 3 and the fabric then drawn over the rods 32, after which the plates 34 and rods 33 will be lowered to the position shown by 15 full lines in Fig. 3, said rods 33 pressing the fabric downwardly where they touch it below the upper level of the rods 32. During 20 the travel of the fabric through the machine it is kept under proper tension and the folds 25 and the like are ironed out of it by the rods 32, 33 and the fabric is directed in smooth condition by the bed 31 to the cutters 18 and pressure disks 19, the latter keeping the fabric pressed firmly against the cutters and 30 operating with said cutters in effecting the subdivision of the width of fabric into strips. The cutters 18 will be spaced on their shaft with respect to the width or widths of strips it may be desired to produce, and the bars 38 35 carrying the pressure disks will be adjusted along their supporting shaft to meet the positions of the cutters.

What I claim as my invention and desire to secure by Letters-Patent, is:

- 40 1. In a machine for slitting fabrics, a series of rotary cutters, a bed against which said cutters act, means for drawing a fabric through the machine, and a tension device for engaging the fabric in advance of said 45 cutters and comprising aligned rods 32, 33 above and below which alternately the fabric passes, and hinged end plates 34 carrying said rods 33 and recessed to pass upon a rod 32; substantially as set forth.
- 50 2. In a machine for slitting fabrics, a series of rotary cutters, a series of rotary pressure disks for coöperation therewith, a series of bars carrying at one end said disks, springs acting against the other ends of said 55 bars, a support for said bars and means for effecting the raising and lowering of said support; substantially as set forth.

3. In a machine for slitting fabrics, a series of rotary cutters, a series of rotary pressure disks for coöperation therewith, a series of bars carrying at one end said disks, springs acting against the other ends of said bars, a rod supporting said bars, a shaft carrying cams supporting said rod, and means 60 for imparting motion to said shaft for actu-

ating said cams, said cams having surfaces for effecting the raising and lowering of said rod and bars; substantially as set forth.

4. In a machine for slitting fabrics, a series of rotary cutters, a series of rotary pressure disks for coöperation therewith, a series of bars carrying at one end said disks, springs acting against the other ends of said bars, a rod supporting said bars, a shaft carrying cams supporting said rod, and means 70 for imparting motion to said shaft for actuating said cams, said cams having three surfaces for maintaining said rod and bars in their extreme upper and lower positions and at an intermediate position; substantially as 75 set forth.

5. In a machine for slitting fabrics, a series of rotary cutters, a series of rotary pressure disks for coöperation therewith, a series of bars having forked inner ends carrying 80 spindles upon which said disks are mounted, springs acting against the other ends of said bars, a support for said bars, and means for effecting the raising and lowering of said support; substantially as set forth. 90

6. In a machine for slitting fabrics, a series of rotary cutters, a series of rotary pressure disks for coöperation therewith, a series of bars having forked inner ends carrying spindles upon which said disks are mounted, 95 springs acting against the other ends of said bars, means for adjusting said springs, a support for said bars, and means for effecting the raising and lowering of said support; substantially as set forth. 100

7. In a machine for slitting fabrics, a series of rotary cutters, a series of rotary pressure disks for coöperation therewith, a series of bars carrying at one end said disks, springs acting against the other ends of said 105 bars, a support for said bars and means for effecting the raising and lowering of said support, said springs being of bar character and fastened at one end to said bars, while at their other ends they are flexed against a 110 stationary part of the machine; substantially as set forth.

8. In a machine for slitting fabrics, a series of rotary cutters, a series of rotary pressure disks for coöperation therewith, a series 115 of bars carrying at one end said disks, springs acting against the other ends of said bars, a rod supporting said bars, and means for effecting the raising and lowering of said rod and bars, said springs being of bar 120 character and at one end flexed against a stationary part of the machine while at their other ends they are provided with grooved shoes to enter inclined recesses in said bars and be detachably secured therein; substantially as set forth. 125

9. In a machine for slitting fabrics, a series of rotary cutters, a series of rotary pressure disks for coöperation therewith, a series of bars having forked inner ends carrying 130

spindles upon which said disks are mounted, springs acting against the other ends of said bars, a rod supporting said bars, and means for effecting the raising and lowering of said rod, said bars being provided with bearings fitting said rod; substantially as set forth.

10. In a machine for slitting fabrics, a series of rotary cutters, a series of rotary pressure disks for co-operation therewith, a series 10 of bars having forked inner ends carrying spindles upon which said disks are mounted, springs acting against the other ends of said bars, a rod pivotally supporting said bars,

bifurcated shoes secured on said rod and between the sides of which said bars are positioned, and means for effecting the raising and lowering of said rod; substantially as set forth.

Signed at New York city, in the county of New York and State of New York, this 11th 15 day of January A. D. 1908.

JAMES A. CAMERON.
